ISRAEL BENJAMINS, OF BATHBEACH, NEW YORK.

SUPPORTING AND HOISTING MECHANISM.

1,307,653.

Specification of Letters Patent. Patented June 24, 1919.

Application filed January 23, 1917. Serial No. 144,036.

To all whom it may concern:

Be it known that I, ISRAEL BENJAMINS, a citizen of the United States, residing at Bathbeach, in the county of Kings and State 5 of New York, have invented a new and useful Supporting and Hoisting Mechanism, of which the following is a specification.

My invention relates to improvements in supporting and hoisting mechanisms, in 10 which a column and one or more gripping members have relative motion to each other, and it includes both mechanisms in which said column is movable and mechanisms in which said column is stationary. To the 15 former class belong such mechanisms as the one patented on Dec. 12, 1916, under the title of a Mechanism for supporting and hoisting loads and sundry articles, No. 1,208,458. To the latter class belong mechanisms for supporting in position and hoisting elevators, dumbwaiters, vertically moving platforms, cages, fire-escapes, and any 20 other articles to which my mechanism may be applied.

25 The objects of my invention are:

First. To provide all mechanisms, such as above described, with a means for applying thereto power, preferably that of electric motors, for hoisting the load, without the 30 use of ropes or chains.

2d. To provide said mechanisms of all classes with a means for gradually lowering said load without taxing the skill or attention of the operator, said lowering means 35 being actuated either by an electric motor or by manual or foot power, if desired.

3d. To provide a mechanism for supporting and hoisting a load, such as an elevator car or dumbwaiter box or cage, which is 40 guided by a stationary column or columns, without the use of any ropes or chains.

4th. To have said mechanism simple, durable and inexpensive.

I attain these objects by the mechanism, 45 one specific form of which is shown in the drawings or by any mechanical equivalent or obvious modification of the same.

I also beg to refer to the drawings of said Patent No. 1,208,458 as illustrating sundry 50 modifications of the hoisting mechanism of this application.

In the drawings Figure 1 is a vertical section on the line A—B of Fig. 2 and looking toward the left, showing also part of

the bottom of an elevator car or cage largely 55 diagrammatically and in elevation.

Fig. 2 is a view partly in elevation and partly in section through the line C—D of Fig. 1 looking toward the right.

Similar numerals and letters refer to similar parts throughout the views of the drawings.

11 is part of the bottom of an elevator cage or car, shown as embodying the connections 13 and 13^a for the springs 34 and 65 36, hereinafter described.

12 and 12^a are brackets for attaching to and carrying the box 14 of the supporting gripping member shown in Fig. 2 in elevation and in Fig. 1 in section.

70 14^a are the flanges of said box 14 for connecting the same to said brackets 12 and 12^a by means of suitable fastenings, which are not shown in the drawings.

16 is a stationary column or guide, such 75 as used for elevator cages or cars, which column may have any suitable shape in cross-section.

17, 17 are the movable keys of the supporting gripping member, which keys are 80 shown as having on their inner and outer edges grooves or raceways containing the rolling members 18 and riders 18^a; the latter are shown as smaller in diameter, thereby allowing the rolling members 18 to be 85 in contact with said box 14 and said column 16.

The riders 18^a serve to keep said members 18 from getting out of contact with said 90 box 14 and column 16.

The backs of said grooves or raceways are shown as inclined to said column 16 and to the ends of said box 14, and receding downwardly therefrom.

The rolling members 18 may be either cylindrical or spherical, and their riders 18^a may have any suitable shape.

19, 19 are trip rods shown in Figs. 1 and 2 as connected each at its lower end to one of said keys 17 by means of the studs 20, shown in dotted lines in Fig. 1, and at its upper end to the lever 21 by means of the pin 22.

Said lever 21 is shown in Fig. 2 as pivotally connected to the bracket 12 by means 105 of the pin 23 and as embodying the loop 15 for connecting to the lower end of said spring 36, and carrying the cam roller 41,

which is actuated by the cam 39 carried by the shaft or spindle 37, which is supported by suitable bearings carried by the bracket 12^a.

5 Said pin 28 is omitted from Fig. 1 for the sake of clearness.

24 is the box of the hoisting gripping member, which is shown in Fig. 1 as extensibly connected to said keys 17 by means of the springs 25, 26, shown as hooked at their upper ends to rings 17^a, formed at the lower ends of said keys 17, and at their lower ends to similar rings 24^a, formed at the ends of the lugs 24^b of said box 24.

15 24^c are bosses, shown in Fig. 1 as formed on the sides of said box 24 at the upper end thereof, which bosses 24^c are adapted to be depressed by the heads 17^b of the keys 17, for the purpose hereinafter described.

20 27, 27 are the movable keys of the hoisting gripping member, which keys are shown in Fig. 2 as having at their inner and outer edges grooves or raceways, similar to those of the keys 17, and rolling members 28, in 25 contact with said column 16 and with the ends of said box 24 on the inside thereof, also riders 28^a, similar to 18^a, and serving the same purpose as above described.

29, 29 are connecting rods, shown in Fig. 30 2 as secured at their lower ends to said keys 27 by means of the studs 30, which are shown in dotted lines, and at their upper ends to the lever 31 by means of the pin 32, which is shown in dotted lines in Fig. 1, and 35 35 which is omitted from Fig. 2, for the sake of clearness. Said lever 31 is shown in Figs. 1 and 2 as pivotally connected to the bracket 12 by means of the spindle 33.

34 is a spring, which is shown in Fig. 1 as 40 connecting said lever 31 to the bottom of the elevator cage or car 11; the upper end of said spring is shown as connected to the loop 13^a, which is shown as embodied in the bottom of said car or cage 11, and the lower end of said 45 spring is shown as connected to the loop or ring 15^a embodied in the lever 31, which is shown in Fig. 1 as carrying the cam roller 40, which is in contact with the cam 38, shown as carried by the shaft or spindle 35, supported by suitable bearings, in the bracket 12.

The springs 34 and 36 cause the levers 31 and 21 respectively to pull on the connecting rods 29 and tripping rods 19 respectively.

55 Said tripping rods 19 are transmitting the tension to the keys 17 of the supporting gripping member, which keys 17 are hereby jammed in between the rolling members 18, which are in contact with the inclined ends 60 of the box 14, on the inside thereof, and the rollers 18 which are in contact with the column 16, thereby pressing the latter rolling members against said column 16 with such an intensity that the resistance to rolling of said 65 members 18 becomes greater than the load

on said keys 17, which support the load of the cage or car 11, which load is thereby held in position.

The keys 27 of the hoisting gripping member are shown in Fig. 2 as being in contact at their upper ends with the lower ends of the box 14 of the supporting gripping member, and the upper end of said box 24 of the hoisting gripping member is shown in Fig. 1 as not quite touching the heads 17^b of the keys 17 of the supporting gripping member; the box 24 is then jammed on to the keys 27 by the springs 25, 26, the tension of which springs produces the same effect on the rolling members 28, 28, as the tension of the spring 36 does on the rolling members 18, as above described. When not interfered with, both gripping members serve as supports for the elevator 11 and said column 16, which may be square in 80 cross section if its length be not excessive, and when it is connected only at its ends to the frame of the building.

Should the column 16 be of considerable height and be connected to the frame of the building at one or more points intermediate to its ends, the form of the cross-section of the column may then be such, so as to allow a web for connecting to the frame of the building and also bearing surfaces for the rollers 18 and 28 of the gripping members; the boxes of the gripping members may then be made each with an opening on one side, which is adapted to pass said web with its connections to the frame, while 100 said gripping members are moving up and down the column 16; the center lines of the gripping members may then be separate and at some distance from each other.

When it is desired to raise the elevator 11, the shaft 35 is made to rotate either by an electric motor through a suitable controller, both of which are not shown in the drawings, or by any other motor, such as an oil engine; the shaft 35 causes the cam or eccentric 38 to depress the lever 31 against the tension of the spring 34, which raises said lever 31 when said cam 38 is in its upward phase of motion thereby imparting to said lever 31 a reciprocable motion, which is transmitted by said connecting rods 29 to said keys 27, 27.

During each downward stroke of said lever 31 the action of the rollers 28, as above described, arrests the downward motion of 120 the keys 27, 27, thereby causing the elevator cage or car 11 to move upwardly; the springs 25, 26, pull on the keys 17 of the supporting gripping member during each downward stroke of the lever 31, which corresponds to 125 the upward move or impulse imparted to the cage or car 11, thereby reducing the pressure on the rollers 18 of said supporting gripping member and allow the same to move upwardly without any appreciable 130

friction; these springs 25, 26 may, however, be connected to the box 14 of the supporting gripping member, or to any part which is stationary with relation to the cage or 5 car 11.

When the lever 31 is moved upwardly by said spring 34, the keys 27 of the hoisting gripping member are lifted. The rollers 28 are thereby relieved of pressure, while the 10 spring 36 acts on the lever 21, pulling said lever upwardly, thereby preventing the cage or car 11 from moving downwardly.

The springs 25, 26, then, bring the box 24 up to the keys 27 of the hoisting gripping 15 member, and jam said box 24 on to said keys 27. Said cage or car will be stationary when the cam 38 is out of contact with said roller 40.

When it is required to move the cage or 20 car 11 downwardly, the shaft 37 is caused to revolve by a suitable motor, and the cam 39 is made to depress the lever 21 during part of its revolution against the tension of the spring 36, which lifts the lever 21 25 during another part of the revolution of said cam 39.

When said lever 21 is depressed the motion is transmitted by the trip rods 19, 19, to the keys 17, 17 of its supporting gripping 30 member, thereby releasing the same. The heads 17^b of the keys 17, 17, act on the bosses 24^c of the box 24, thereby somewhat removing said box 24 from the keys 27 against the tension of the springs 25, 26, and there- 35 by releasing the hoisting gripping member.

The clearance, shown in Fig. 1 between the heads 17^b and the bosses 24^c, is provided to secure the tightness of said box 24 on said keys 27 of said hoisting gripping member.

40 The cam 39 is shown in Fig. 2 as having such a shape as to keep the lever 21 depressed during almost one half of the rotation of the shaft 37, and to allow the spring 36 to act on said lever 21 also during almost 45 one half of the rotation of said shaft, the lower part of the cam in Fig. 2 not quite touching the roller 41 during this phase of its revolution.

The transition of the lever 21 from the 50 position of extreme depression to that of its highest lift is made sudden and sharp by the appropriate outline of the cam 39.

The cam 38, on the contrary, is designed to act gradually on the lever 31, as is evident 55 from Fig. 1 of the drawings, thereby gradually raising the cage or car 11.

The outline of the cams 38 and 39 may be different, however, if desired.

The object of the cam 39 is to prevent a 60 too sudden and continuous fall of the load when moving downwardly by successively starting and stopping the gripping members.

Only one hoisting and one supporting gripping member is shown in the drawings; 65 but, for the sake of symmetry of action and

to prevent strains on the mechanism, the gripping members may preferably be used in pairs, either on a pair of columns 16, opposite each other, or, better still, on two pair of columns 16 at the four corners of the 70 cage 11.

Where two hoisting gripping members or two sets of such members in opposite phases are employed, the supporting gripping member or members may be omitted, if desired, 75 unless they be retained for extra safety in the emergency of a breakdown of one or more of the hoisting gripping members.

It is evident that, when the speed of the shaft 35 is very high, the velocity of the cage 80 or car 11 will be nearly uniform, the momentum of the load tending to produce the uniformity of speed.

This result may be still more readily attained by using two hoisting gripping members or two sets of such members working in opposite phases to each other.

The opposite phases of such hoisting gripping members may be secured by suitable 85 gearing or chains and sprockets.

Where the speed of the shafts 35 is very high, the supporting gripping member or members may be omitted even when the hoisting gripping member or members are of one phase of action only, the momentum 95 of the load then being relied on to prevent slip or undue retardation of the cage 11 between successive upward strokes of the hoisting gripping member or members.

The shafts 35 and 37 with the cams 38 and 39 may be employed also respectively for actuating and releasing a hoisting mechanism in which the column 16 is movable, such as in my Patent No. 1,208,458.

I do not, therefore, restrict myself, as far 105 as these general features are concerned, to the mechanism illustrated in the drawings of this application. The several parts of my supporting and hoisting mechanism admit of many modifications, as for example: 110

The keys 17 and 27 may have raceways only on their inner edges, as in Figs. 3 and 4 of said Patent No. 1,208,458; for light 115 loads the riders 18^a may be omitted, and for very light loads even the rolling members 18, 18 may be omitted, and the keys 17 and 27 may then have no raceways.

One of each pair of keys 17 and 27 may be omitted, if desired, or made stationary in each gripping member, as in my Patent on 120 No. 1,075,323.

The supporting gripping member of this application may be used without the hoisting gripping member, where it is desired 125 only to support any load by the mechanism, without raising the same, as in scaffolds, or where other means are employed for raising the load.

The number of grooves or raceways and 130

rolling members of the keys 17 and 27 may be increased for heavier loads and diminished for lighter loads, and the number may even be reduced to one, if desired.

5. The number of keys in each gripping member may be increased, if desired.

The connecting rods 29, 29 of the hoisting gripping member are shown as inclosed by the box 14 of the stationary gripping member; but they may also be located outside of said box, if desired; the boxes 14 and 24 may also be reversed in position, and the triprods 19, 19 may then be inclosed by the box 24, if desired.

15. The supporting gripping member may be made of the same form as the hoisting gripping member, or vice versa, as shown in Figs. 8 and 9 of said Patent No. 1,208,458.

Many other changes could be made in the 20 details and arrangement of parts of my supporting and hoisting mechanism without departing from the main scope of my invention.

I do not, therefore, restrict myself to the 25 form of the design as shown in the drawings, but I intend to include also all mechanical equivalents and obvious modifications of the same.

What I claim as my invention, and desire 30 to secure by Letters Patent, is:—

1. In a hoisting mechanism the combination of a load carrier, a substantially vertical column, a gripping member adapted to be operated from said carrier and automatically to engage said column, and a revolving cam supported by said carrier and adapted to actuate said gripping member, thereby lifting said carrier.

2. In a hoisting mechanism the combination of a load carrier, a substantially vertical column, a gripping member adapted to be operated from said carrier and automatically to engage said column, a revolving cam supported by said carrier and adapted during 45 part of each revolution thereof to actuate said gripping member, thereby lifting said carrier, and a means for automatically returning said gripping member to its original position with relation to said cam after 50 each lifting phase of its revolution.

3. In a hoisting mechanism the combination of a load carrier, a substantially vertical column, a gripping member adapted to be operated from said carrier and automatically to engage said column, a revolving cam supported by said carrier and adapted during part of each revolution thereof to actuate said gripping member, thereby lifting said carrier, and a spring supported by 55 said carrier and adapted automatically to return said gripping member to its original position with relation to said cam after each lifting phase of its revolution.

4. In a supporting mechanism the combination of a load carrier, a substantially ver-

tical column, a gripping member adapted to be operated from said carrier, and automatically to engage said column, thereby sustaining said carrier, and a revolving cam supported by said carrier and adapted during part of each revolution thereof to release said gripping member thereby gradually lowering said carrier.

5. In a supporting mechanism the combination of a load carrier, a substantially vertical column, a gripping member adapted to be operated from said carrier and automatically to engage said column, thereby sustaining said carrier, a means for normally retaining said gripping member in engagement with said column, a revolving cam supported by said carrier and adapted during part of each revolution thereof to release said gripping member in opposition to the force of said retaining means and to allow said retaining means automatically to act on said gripping member after the releasing phase of each revolution of said cam, thereby gradually lowering said carrier.

6. In a supporting mechanism the combination of a substantially vertical column, a load carrier, a gripping member adapted to be operated from said carrier and automatically to engage said column, thereby sustaining said carrier, a spring supported by said carrier and adapted normally to retain said gripping member in engagement with said column, a revolving cam supported by said carrier and adapted during part of each revolution thereof to release said gripping member in opposition to the force of said spring, and to allow said spring to act on said gripping member after the releasing phase of each revolution of said cam, thereby gradually lowering said carrier.

7. In a supporting mechanism the combination of a substantially vertical column, a load carrier, a gripping member supported by said carrier and adapted to be operated from said carrier and to engage said column by means of rolling members situated in raceways in said gripping member, said raceways conveying toward said column at their upper ends and recessing downwardly from said column at their lower ends, thereby causing said rolling members to be jammed in said raceways by the downward pressure of said gripping member and thereby sustaining said carrier, and a means for releasing said gripping member.

8. In a hoisting mechanism the combination of a substantially vertical column, a load carrier, a gripping member supported by said carrier and adapted to be operated from said carrier and to engage said column by means of rolling members situated in raceways in said gripping member, said raceways conveying toward said column at their upper ends and receding downwardly from said column at their lower ends,

thereby causing said rolling members to be jammed in said raceways by the downward pressure of said gripping member and thereby sustaining said carrier, a means for operating said gripping member, said means being adapted alternately to raise said carrier by leaning on said gripping member as a fulcrum in a series of successive strokes and to raise said gripping member by leaning on said carrier as a fulcrum during each return stroke, and a means for sustaining said carrier during each return stroke.

9. In a hoisting mechanism the combination of a load carrier, a substantially vertical column, an automatic gripping member adapted to be operated from said carrier and automatically to engage said column, thereby lifting said carrier in a series of successive strokes and an automatic means for sustaining said carrier during each return stroke of said gripping member, said sustaining means being connected to said carrier and adapted to move therewith.

10. In a supporting mechanism the combination of a load carrier, a substantially vertical column, an automatic gripping member adapted to be operated from said carrier and automatically to engage said column, thereby sustaining said carrier, and an automatic means for releasing said gripping member, said means being connected to said carrier and adapted to move therewith.

11. In a hoisting mechanism the combination of a load carrier, a substantially vertical column, a gripping member adapted automatically to engage said column, and to lift said carrier in a series of successive strokes, a revolving cam adapted during part of each revolution thereof to actuate said gripping member, a means for automatically returning said gripping member to its original position with relation to said cam after the lifting phase of each revolution thereof and a means for sustaining said carrier during each return stroke of said gripping member.

12. In a supporting mechanism the combination of a load carrier, a substantially vertical column, a gripping member adapted automatically to engage said column, thereby sustaining said carrier, a means for normally retaining said gripping member

in engagement with said column and a revolving cam adapted during part of each revolution thereof to release said gripping member in opposition to the force of said retaining means and to allow said retaining means automatically to act on said gripping member after the releasing phase of each revolution of said cam, thereby gradually lowering said carrier.

13. In a supporting mechanism a substantially vertical column, a load carrier, an interiorly tapered box supported by said carrier, and adapted to move therewith, one or more tapered keys in said box, said keys being adapted to engage said column, a means for normally retaining said keys in engagement with said column, thereby sustaining said carrier, and a means for disengaging said keys from said column, thereby releasing said carrier, said retaining means and said disengaging means being supported by said carrier and adapted to move therewith.

14. In a hoisting mechanism a substantially vertical column, a load carrier, an interiorly tapered box extensibly supported by said carrier and adapted to move therewith, one or more tapered keys in said box, said keys being adapted to engage said column, a means for operating said keys supported by said carrier, said means being adapted alternately to raise said carrier by leaning on said keys as a fulcrum in a series of successive strokes and to raise said box and keys during each return stroke by leaning on said carrier as a fulcrum and a means for sustaining said carrier during each return stroke, said sustaining means also being supported by said carrier and adapted to move therewith.

15. In a hoisting mechanism one or more stationary columns, a load carrier adapted to be guided thereby, one or more pairs of automatic hoisting gripping members adapted to engage said column or columns, thereby hoisting said carrier, said gripping members being in opposite phases, thereby making the motion of said carrier more uniform, and an automatic means for actuating said gripping members, supported by said carrier.

ISRAEL BENJAMINS.
